UNITED STATES PATENT OFFICE

2,084,347

AUTOMATIC PERFORATING MACHINE

Lincoln Mathew Keefe, Springfield, Mass.

Application November 5, 1934, Serial No. 751,467

20 Claims. (Cl. 164—115)

This invention relates to improvements in automatic perforating machines and has for a principal object the reproduction of punched record cards in their original form or in any other desired form or arrangement.

A further object of the invention is the provision in a punching machine of a sensing means adapted to read or analyze the records to be reproduced in horizontal rows across the records 10 step by step.

A further object of the invention is the provision of a punching machine having a sensing means and a row of punches, the brushes of the sensing means and the row of punches being in 15 alignment in the machine and adapted to operate substantially simultaneously.

Still another object of the invention is the provision in a punching machine of a single actuating member and a plurality of punches associated therewith, having electrically actuated interposers designed to be moved into operative positions between the actuating member and the one or more of the punches, and the termination of the magnets controlling said interposers in a 25 plug board so that said magnets may be selectively connected to means sensing the card to be reproduced in any desired order or arrangement.

Another object of the invention is the provision in an automatic reproducing punch of a 30 card feeding mechanism adapted to feed to the machine simultaneously in steps a perforated record and a blank record.

A still further object of the invention is the provision in an automatic duplicating punching 35 machine of a single movable member carrying pickers adapted to feed into the machine at the same time both a card to be reproduced and a blank card to be perforated.

Other objects will be apparent to those skilled 40 in the art upon a perusal of these specifications and the appended claims.

Duplicating punches of the prior art such as that described in Patent No. 1,772,186 to Fred L. Lee et al. or Patent No. 1,921,408 to Wm. F. 45 Gutgesell, were designed mainly to reproduce a portion of a record card automatically after which additional data may be punched into the card by means of hand-operated keys.

In the machines of the prior art, the record 50 to be duplicated is sensed vertical column by vertical column therefore making it necessary, if the whole card were to be duplicated, to take 45 steps if a 45 column record were being duplicated or 80 steps if an 80 column record were being 55 duplicated.

Permanent electrical connections interconnect the sensing means and the magnets actuating the punches.

In the new and improved reproducing punch the sensing means senses all of the vertical columns of the record to be reproduced in horizontal rows, index position by index position, much in the same manner as records are sensed in a tabulating machine with the exception that there is a dwell at each index position. There 5 are 12 dwells for either a 45 or an 80 column record thereby making it possible to reproduce records in from one fourth to one seventh the time required to duplicate entire records by the machines of the prior art.

In existing machines of a similar character the magnets actuate the punches thereby drawing heavy current. In the new and improved device the punches are mechanically driven and are controlled by small electro-magnets. These 20 magnets terminate in sockets in a plug board and the brushes of the sensing means also terminate in sockets in the plug board so that the sensing means and the control magnets for the brushes 25 may be interconnected in any desired arrangement making it possible to omit any portions of the records not desired to be duplicated in the new records, and to also arrange the perforations in the new records in any conceivable arrangement regardless of how they appear in 30 the original. This makes it possible to reproduce data from a 45 column record to an 80 column record or vice versa; or to reproduce a 90 column record into a 45 or 80 column record or vice versa.

In the preferred embodiment shown and illustrated herein, the reproduction of an 80 column record from an 80 column record is described but it is obvious that by merely rearranging the elements disclosed it is possible to reproduce any 40 type of record from a similar or other type of record and in any conceivable arrangement.

Referring to the drawings:

Figure 1 is a perspective elevation showing the arrangement of the various elements in the 45 new and improved perforating machine.

Figure 2 is a sectional elevation showing details of the record feed, details of the punches and the mechanical actuator.

Figure 3 is an elevation, partly in section, 50 showing details of the feeding mechanism and mechanism for insuring the correct registration of the index positions on the record with the punches.

Figure 4 is an elevation, partly in section, 55

showing the record feed mechanism feeding a new record to the punches after having ejected the previously completed record.

Figure 5 is an elevation, partly in section, showing one of the punch control members in its control position and showing the punch at the extreme limit of its stroke.

Figure 6 is a plan view of a portion of the mechanism showing the arrangement of one of the punch driving cams and the punch actuating member.

Figure 7 is a circuit diagram showing schematically the controls of the new and improved device.

For the sake of clarity portions of the supporting frame bearing for the various shafts and portions of the plug board have been omitted so that a clear understanding of the elements of the machine and their relation to each other may be had.

The record to be reproduced, which may be termed the control record, is designated by the numeral 10 and the blank record, which is to be punched in the machine is designated by the numeral 11. These records are moved from the bottom of their respective stacks, 12 and 13, by means of pickers 14, 15, 16 and 17 carried by a single shaft 18.

The picker shaft 18 has secured thereto and is adapted to be driven thereby, a dog 19. A shaft 20 has one end operatively connected to dog 19 by means of a clevis pin 21. The other end of the shaft 20 is operatively connected to a lever 22 by means of a pin 23 passing through a yoke 25. The lever 22 is supported on a pivot pin 24 which may be suitably supported on the frame of the machine, not shown.

A yoke 26 formed in the lever 22 has passing therethrough a pin 28 which forms a support for a roller 27, and a cam 29 secured to the main shaft 30 is operatively engaged by the roller 27.

When the shaft 30 rotates the high portion 29a of the cam 29 acting against the roller 27 causes the lever 22 to move in a counterclockwise direction as found in Figure 1 and through the medium of the shaft 20 the dog 19 is pulled and thereby the shaft 18 is caused to rotate through a small arc in a clockwise direction. When this occurs the pickers 14 and 15 engage the control record 10 and the pickers 16 and 17 engage the blank record 11 and thereby both of the records are advanced to the feed rollers of the machine which will presently be described.

By the time the high portion 29a of the cam 29 has passed the roller 27 the lever 22 starts moving in a clockwise direction on its pivot 24 and through the medium of the shaft 20 the dog 19 moves in a counterclockwise direction thereby returning the pickers to their normal position.

To insure that the roller 27 is always in contact with the cam 29, the dog 19 is provided with an arm 31 having a slotted portion 34 through which a pin 33 is passed. A spring 32 has one end thereof secured to the pin 33 and the other end of it may be secured to a portion of the frame, not shown.

The machine is provided with feed roll shafts 35, 36 and 41, 42. These shafts are supported on suitable bearings in the frame, not shown. The shaft 35 carries a plurality of feed rollers, one of which is designated by the numeral 37, and the shaft 36 carries a plurality of feed rollers, one of which is designated by the numeral 38. Each feed roller 37 is positioned substantially in line with a feed roller 38 so that together they engage a record and propel the same through the ma-

chine. This necessitates that the shaft 35 and shaft 36 rotate in opposite directions.

Accordingly, the shaft 35 has secured thereto a pinion 39 and the shaft 36 carries a pinion 40 which meshes with the pinion 39. These pinions are driven by a gear 41. It has been found preferable for constructional reasons to have the gear 41 drive the pinion 40.

The shaft 41 has secured thereto a plurality of feed rollers, one of which is designated by the numeral 43, and the shaft 42 carries a plurality of feed rollers, one of which is designated by the numeral 44. The feed rollers 43 and 44 are grouped in cooperative pairs in the same manner as the feed rollers 37 and 38 previously described.

The shaft 41 has secured thereto a pinion 45 which meshes with a pinion 46 carried by the shaft 42, and the gear 41 also drives the pinion 46.

The sensing means and the punches, which will presently be described, are arranged in endwise relation with a series of teeth 53 and a projecting arm 54. The arm 54 carries a spud shaft 55 which forms the support for a pawl 56. The pawl 56 is held into engagement with the teeth of the ratchet 51 by means of a spring 57.

A bar 58 has a rack 59 formed along one face of its lower end and has the opposite, or upper end in the form of a ball 60. The rack 59 engages the teeth 53 of the sector gear 52 and is held into engagement therewith by means of a grooved roller 61 supported on a shaft 62 a fixed distance from the shaft 49.

A lever 64 has one end thereof pivoted on a pin 65 supported in a yoked portion 66 of the frame. The other end of the lever 64 is slotted and is provided with a pin 67 substantially parallel to the pin 65 forming a bearing for a roller 68 and positioning the same in operative relation to the cam 48. The lever 64 is also provided with a socket 69 which is engaged by a ball 60. The ball 60 is held into engagement with the socket 69 by means of a spring 63, one end of which is secured to the bar 58 and the other end of which is secured to a portion 70 of the frame by means of an escutcheon pin 71.

When the shaft 30 is rotated the cam 48 acting against the roller 68 drives the bar 58 downward and the rack 59 moves the sector gear 52 in the direction of the arrow (Figures 3 and 4). Due to the fact that the pawl is in engagement with the teeth of the ratchet 51 the movement of the sector gear 52 in the direction of the arrow causes the ratchet to also move in the direction of the arrow together with the shaft 49, the star wheel 50 and the gear 41. This causes the feed roll shafts 35, 36 and 41, 42 to rotate through the medium of the pinions 40, 39 and 46, 45 in the direction indicated individually by arrows and thereby the records are advanced through the machine.

The star wheel 50 is secured to the shaft 49 and/or the gear wheel 41 in such a position relative thereto that its stars or teeth are in definite timed relation to the index rows of the records.

A roller 72 engages the teeth of the star wheel 50 and is provided to insure accurate registration of the index rows of the records with the punches and with the sensing means. This roller is carried by a yoked lever 74, a pin 73 being provided as a bearing for the roller 72. The lever 74 is supported in a pivot shaft 75 secured to the frame in any suitable manner and an arm 76 extending from the lever 74 has secured thereto a spring 77, one end of which may be secured to the frame. This spring causes the

roller to firmly but resiliently engage the teeth of the star wheel 50.

The cam 48 is provided with a plurality of small lobes one of which is designated by the 5 numeral 48a, and a large lobe 48b which feeds one set of records out of the machine and a second set of records into the machine. This lobe is of such length that the records being fed into the machine come to rest with the first index 10 rows thereon in position in the sensing means, and beneath the punches respectively.

Suitable receptacles or pockets are provided to receive and stack the records ejected from the machine. These pockets are designated by the 15 numeral 78. As the records are ejected by the rollers they encounter a suitable deflector 79 which is provided to direct the records into the pockets 78. The deflector may be suitably pivoted on a fixed shaft 80 suitably supported on 20 the frame.

The hoppers containing cards to be fed into the machine may be of any suitable form and in the embodiment shown a portion of a card hopper is designated generally by the numeral 81. 25 This hopper is arranged so that it is possible only to feed one record at a time.

Having described the steps in feeding the records into and through the machine, a description of the punches will be given, followed by a 30 description of the sensing means and the method of associating elements of the sensing means with the control elements of the punches.

It has been the usual practice to propel the punches through the records by means of electro-magnets. Such arrangements are shown 35 and described in the Lee et al. and the Gutgesell patents above referred to. This arrangement has distinct disadvantages in that heavy currents are required to exert sufficient power upon the 40 punches to effect the perforations of the records.

In the new and improved perforating machine the punches are driven or propelled through the material to be punched by mechanical means and control of the mechanical means is effected 45 by electrical means. The moving parts associated with the electrical means are very light in construction and so no work is done by the magnets other than shifting these moving parts into alignment with heads of the punches. Due to 50 the small current used the sensing means does not have to handle heavy currents.

Referring to Figure 2, a suitable cross member 82 of the frame is provided with a die block 83. The die block 83 is provided with a plurality of 55 dies, one of which is designated by the numeral 84. In the present embodiment this die block 83 is provided with eighty rectangular dies. In cases where it is desirable to reproduce forty-five or ninety column records the dies would be round 60 and forty-five dies would be provided instead of eighty.

A second cross member 85 is spaced apart from the cross member 82 a sufficient distance with clearance for a record card to pass therethrough. 65 A stripper block 86 is set in the cross member 85 flush with the lower surface of the latter. The stripper block is provided with a plurality of rectangular holes which serve as guides for the punches 87. The cross member 85 is provided with a slot 88 which is of substantially the width of the punches plus clearance. The punches are all provided with notches 89, and a longitudinal plate 90 engages all of the slots 88 thereby preventing the punches from falling 70 out of the stripper block when the cross mem- 75

ber 85 is removed from the machine and turned upside down. The punches are provided with T-shaped heads 91 which are utilized both to propel the punches into the dies and to positively withdraw them from the dies after a punching operation as will presently be described.

A single mechanical member is adapted to actuate all of the dies, either singly or in combination, in accordance with electrically actuated controls which will later be described.

The punch actuating member designated generally by the numeral 92 is comprised of a reciprocable body member 93 supported on and adapted to reciprocate on slides (not shown).

The body member 93 has secured thereto an L strip 94 and a second L strip 95. These strips are secured to the body member 93 by any suitable means such as, for example, screws 96.

The angle portions of these L's respectively engage opposite sides of the punches 87 below the 20 T-shaped heads 91 thereof.

It will be noted, referring to the drawings, that there is a substantial space between the T-shaped heads 91 of the punches and the lower edge of the body member 93. This space is provided for interposers associated with the electrical controls above referred to and to be presently described. It is obvious that when the punch actuating member 92 is actuated the punch cannot be driven unless something occupies the space between the T-shaped head 91 and the bottom of the body member 93.

The shaft 30 also carries cams 96 and 97 which are provided respectively with lobes 98 and 99 corresponding to the horizontal rows of index positions in the records.

The body member 93 is provided with a plurality of stud shafts one of which is designated by the numeral 100, which support rollers 101 and 102. These rollers are provided with suitable 40 bearings, for example, ball bearings. The roller 101 is adapted to be actuated by lobes 98 on the cam 96 and the roller 102 is adapted to be actuated by lobes 99 on the cam 97. When the shaft 30 is rotated, the cams which are fixed on the 45 shaft rotate therewith and considering the rotation in the direction indicated by the arrow, when the first lobe 98 of the cam 96 engages the roller 101, the first lobe 99 on the cam 97 engages the roller 102, thereby propelling the body member 50 93 downward a distance equal to the height of the lobes 98 and 99.

The L strip 95 is provided with a plurality of openings 103 communicating with the internal space formed by the L strips 94 and 95. The 55 openings 103 serve as guides for the interposers 104.

The interposers 104 are each provided with a rounded head 105 and a rounded tail 106. The frame 70 is provided with a plurality of slot openings 107 which are preferably in line with the openings 103 in the L strip 95. Each of slotted openings 107 is provided with a block 108. The tail 106 of each of the interposers is pivotally mounted in a block 108 and the blocks are adapted to reciprocate in the slotted openings 107. Each of the blocks 108 has secured thereto in an opposite end from that of the interposer tail, a rod 109. A single assembly comprising a rod 109, a block 108 and an interposer 104 is provided for each punch. Each rod 109 is operatively connected to an armature 110 and a spring 111 connected thereto tends to hold the assembly in its extreme position to the right, as shown in Figures 1 and 2, with the interposer 104 out of en- 70 75

gagement with its associated punch. As the body member reciprocates, the interposers swing slightly about their pivots formed with the blocks 103 and the outer ends 105 move freely in the 5 openings 103.

The opposite end of the spring 111 may be secured to a fixed portion of the machine, for example, to a pin 112 supported by a portion of the frame 78. The armature 110 is associated with 10 an electro-magnet 113. This electro-magnet is provided with windings and may be of any preferred form of construction. An electro-magnet 113 and an armature 110 are associated with each rod 109.

15 Each assembly comprised of an interposer 104, a block 108, a rod 109, an armature 110 and an electro-magnet 113, constitutes a controlling member for each punch. As the electro-magnets do not actually drive the punches, very small 20 currents may be utilized to actuate the magnets, and accordingly the sparking at the sensing means which will presently be described, is cut down to a minimum. When an electro-magnet is actuated, the interposer 104 is moved into position between the body member 93 and the T head 81 of a punch 87, after which a lobe 98 of the cam 96 acting against the roller 101 and the action of a similar cam and roller previously described, cause the body member 93 to move 25 downward and the punch 87 to perforate the record 11.

The magnets 113 terminate in a series of jacks or sockets 114 in a plug board 115 so that they may readily be interconnected with other jacks 30 or sockets in the plug board which will presently be described.

The cross members 82 and 85 containing the die block and the stripper block respectively are in line with the hopper or stack of blank records 40 and when a blank record 11 is fed by the pickers 16 and 17, the feed rollers 37, 38, feed the record past the punches in accordance with the arrangement of the lobes 48a on the cam 48. The control records 10 are fed past a sensing means in steps synchronously with the movement of the blank record past the punches and dies. In the preferred form, the sensing means includes a bar 116 of insulation supported on the frame in any suitable manner and containing a 45 plurality of metallic brushes 117. These brushes are insulated from each other and each brush is connected by means of a wire, one of which is shown at 118, to a jack or socket 119 in the plug board 115. The brushes 117 make contact with a contact roller 102 through holes in the control record. A contact shoe 121 bears against the roller 102 and a wire 122 connects the contact shoe 121 to a contact arm 194 which will presently be described. A pinion 124 is secured to 50 the shaft 35, and a shaft 125 supports the roller 120 and has secured thereto a pinion 126 which meshes with the pinion 124 so that whenever the shaft 35 moves, the roller 120 is rotated thereby, always presenting a clean surface 55 to the brushes 117.

60 In the embodiment shown, the control record has eighty columns; therefore, the machine would be provided with eighty sensing brushes 117, one in line with each vertical column of the record. By means of plug wires, one of which is shown at 127, any desired brush or brushes of the sensing means may be connected to any control magnet 113 controlling the punch corresponding to any column of the record to be punched. By this 65 arrangement, it is possible to reproduce a record, 70

either wholly or in part, with the columns in the same order as the control record or in any other desired order or arrangement.

A fuse clip 128 is connected by a wire 129 to a stationary contact block 130. A suitable contact 131 is carried by the block 130 and a movable contact 132 is carried by an arm 133. The arm 133 carries an insulated bumper 134 which is engaged by a cam 135 secured to the shaft 30. The arm 133 is preferably made of springy material and may be insulatedly supported on the frame in any suitable manner. The lobes 135a of the cam 135 engage the insulating bumper 134 and move the contact 132 into engagement with the contact 131 thereby connecting the return circuit of all of the magnets 113 to the fuse clip 128. The return circuit of each of the magnets 113 may be provided with a suitable resistor 136, and the contacts 131 and 132 may be bridged with a condenser 137 and a series resistor 138. 15

20 A suitable connector cord 139 is provided for connecting the machine to a suitable source of current. This cord connects to the fuses 140 and 141. The shaft 30 is provided with a gear 142. A pinion 143 meshes with the gear 142 and is driven by a motor 144. One side of the motor 144 is connected by a wire 145 to a series of control elements which will presently be described, and a wire 145a connects the fuse clip 123 of the fuse 140 to said controls. A suitable switch 147 is provided in the wire 145 for controlling the current supplied to the device. 25

In connection with the figures above described, various control elements for keeping the machine running and feeding cards, for stopping the machine due to the absence of either control records or blank cards, at the sensing means and/or the punches etc., have been omitted for the sake of clarity. These elements and their correlation to the various parts of the device 30 are shown in Figure 7.

35 Current from the positive side of the source of current is led via a fuse 140, a switch 147 and a wire 145a to a contact arm 149 carrying contact point 150. A contact arm 151 carries a 40 contact point 152.

The contact arm 149 and the arm 151 are secured together with their respective contact points in cooperative relation by means of a block of insulation 153, and a contact arm 154 carrying 50 a contact point 155 is mounted in cooperative relation with a contact arm 156 carrying a contact point 157, by means of an insulating block 158.

55 A push rod 159 provided with a push button 160 is arranged in sea-saw relation with a push rod 161 having a push button 162 by means of an arm 163 pivoted at 164. The bar 163 is slidably connected to the push rods 159 and 161 at 165 and 166 respectively. The push rod 159 is provided with an insulating tip and is adapted to act against the contact arm 149. The push rod 161 is also provided with a suitably insulated tip and acts against the contact arm 156. The push button 160, when operated, closes the contacts 60 150, 152 and starts the device operating as will presently be described. This button 160 may be termed the "start" button. The push button 162 when pushed causes the push rod 161 to move the contact arm 156 thereby opening the contacts 155, 157 with the result that the device stops operating at the completion of a card cycle as will be presently described. This may be termed a "stop" button. Normally the contacts 150, 152 are open and the contacts 155, 157 are closed. 65 70 75

As stated above, the wire 145a connects to the contact arm 149. This wire is also connected to the contact arm 171 by means of a wire 229. The contact arm 151 is connected, by means of a wire 168, to a contact arm 169 and to a magnet 170.

The contact arm 169 carries a contact point 171, and a stationary contact block 172 carries a contact point 173. Whenever the magnet 170 is energized the contact arm 169 is attracted and the contact points 171, 173 are closed. The stationary contact block 172 is connected by means of a wire 174 to the wire 145 which is in turn connected to the motor 144. It is also connected 15 to the contact lever 200 by means of a wire 207.

The return wire of the magnet 170 is connected by means of a wire 175 to the wire 129 which is in turn connected to the negative fuse 141. The contact arm 154 is connected by means of a wire 20 176 to a contact block 180 carrying a contact point 179. A cooperative contact point 178 is carried by a movable contact arm 177. A magnet 181 controls the movement of the arm 177. The contact points 178, 179 are normally closed and 25 remain in this relation until the magnet 181 is energized. The return wire of the magnet 181 is connected to the wire 175 and to the negative fuse 141. The other end of the winding of the magnet 181 is connected by means of a wire 182 30 to card lever contacts which will presently be described.

A contact arm 231 carries a contact point 232 and a contact point 234 is carried by a contact arm 233 in cooperative relation to the contact 35 point 232. The contact arm 231 is provided with an insulating member 236 which is adapted to be engaged by the contact arm 171.

The contact arm 233 is connected to the wire 182 by means of a wire 237 and the contact 40 arm 231 is connected to the wire 174 by means of a wire 238.

Whenever the magnet 181 is energized the contact arm 171 is attracted and the movement of the arm opens the contact points 178 and 179 45 and closes the contact points 232 and 234. The act of opening the contact points 178 and 179 interrupts the current flowing via the wire 239, the contact points 192 and 195 and the wire 122 to the contact shoe 121 thereby de-energizing 50 the sensing means.

A contact lever 183 is mounted on a pivot 184 and carries a roller 185 and a contact point 186. A stationary contact member 187 is provided with a contact point 188 which is positioned in operative relation with the contact point 186. A cam 189 may be mounted on and secured to the shaft 30. This cam is provided with a lobe 189a and is so timed that the contact points 186, 188 are opened immediately after the last 55 rows in the index positions in the control card and in the card to be punched leave the sensing means and the punches respectively, and until just before the first rows of index positions in the succeeding records reach the sensing means 60 and the punches respectively.

The contact member 187 is connected by means of a wire 190 to the wire 145 which is in turn connected to the motor 144.

A contact arm 191 is provided with a contact 70 point 192 and an insulating button 193. This contact arm is connected via a wire 239 to the contact arms 154 and 180. A contact arm 194 carrying a contact point 195 is secured in operative relation with the contact arm 191 by 75 means of a block of insulation 196. A wire 122

connects the contact arm 194 to the contact shoe 121 thereby supplying current to the contact roller 120 so that the brushes 117 may contact the roller through holes in a control record and thereby institute impulses which are delivered 5 by wires 118 to a series of jacks 119.

The contact lever 183 is provided with an extension 197 which is in operative relation to the insulating button 193. When the roller 185 is engaged by the lower portions of the surfaces of the cam 189 there is a slight clearance between extension 197 and the button 193. When the lobe 189a of the cam 189 actuates the roller 185, the extension 197 bearing against the insulating button 193 moves the contact arm 191 to the right as shown in Figure 7, thereby separating the contacts 192, 195 and cutting off the current from the contact roller 120. The cam 189 is so timed that the lobe 189a actuates the lever 183 via the roller 185 during the time when the last 10 row of index points in one record leaves the sensing means and the first row of index points in a succeeding record reaches the sensing means.

The shaft 30 may also carry a cam 198 which is provided with a lobe 198a. A contact lever 200 is provided with a pivot 199 and a contact point 201. The contact arm 200 also carries a roller 204 which is engaged by the cam 198. A spring 205 bearing against a post 206 keeps the roller 204 into engagement with the surfaces of the cam 198. A stationary contact block 203 carries a contact point 202 with which the contact point 201 cooperates. The contact lever 200 is connected by means of a wire 207 to the stationary contact block 172 and to the motor 144 via 20 the wires 174 and 145. The stationary contact member 203 is connected by means of a wire 208 to card lever contact devices to be presently described.

The lobe 198a of the cam 198 is so timed that the contact points 201, 202 are closed from the time the leading edge of the records during each cycle reaches the sensing means and the punches respectively until the 9th row of index positions reaches the sensing means and punches respectively. The stationary contact block 203 is connected by means of the wire 208 to a contact arm 209 carrying a contact point 210. A contact arm 211 carries a contact point 212 in cooperative relation with the contact point 210. A contact block 213 holds the contact arms 209 and 211 in proper relationship. 40

A contact arm 214 carries a contact point 215 in cooperative relation with a contact point 216 carried by a contact arm 217. The contact arms 214, 217 are held in cooperative relationship by means of a block of insulation 218.

A card lever 220 is provided with a suitable pivot 221 and has a push rod 219 pivoted thereto. The push rod 219 is provided with a suitable insulating button 222 which is adapted to actuate the contact arm 211 whenever the card lever 220 is engaged by a record.

The card lever 220 is so positioned relative to the sensing means that it is engaged by a control record during each card cycle and while so engaged the contact points 210, 212 are open.

A card lever 223 is provided with a suitable pivot 224 and has a push rod 225 pivoted thereto. The push rod 225 is provided with a suitable insulating button 226 which is adapted to actuate the contact arm 217 and thereby open the contact points 215, 216. The card lever 223 is so positioned relative to the punches 81 that it is engaged by a record to be punched during each 70 75

card cycle and while so engaged the contact points 215, 216 are open.

The contact arm 209 is connected to the stationary contact block 203 by means of a wire 208 as above stated. The contact arm 214 is connected in common with the contact arm 209 by means of a wire 227.

The contact arm 211 and the contact arm 217 are connected in common by a wire 228 which is 10 in turn connected to the wire 182 leading to the winding of the magnet 181 and via the wire 237 to the contact arm 233.

By means of these connections the two pairs of contact arms associated with the card lever 15 contacts are connected in parallel between the stationary contact block 203 and the winding of the magnet 181.

The cams 189 and 198 are so timed in the shaft 30 that the contact arm 183 is engaged by 20 the lobe 188a of the cam 189 and the contact points 186, 188 are opened and at the same time the contact arm 191 is actuated by the extension 197 and the contact points 192 and 195 are opened. The lobe 198a of the cam 198 is in engagement with the roller 204 causing contact to be established between the contact points 201, 202. The machine always comes to rest with the cams in the relation just stated.

With the machine at rest, it may be started 30 into operation by pressing the "start" button or key 160 thereby closing the contact points 150 and 152 and allowing current to flow via the wire 168 to the magnet coil 170 and via the wire 175 and the wire 129 to the negative side of the line. 35 The magnet 170 upon becoming energized attracts the arms 169 and closes the contacts 171 and 173 thereby allowing current to flow via the wires 174 and 145 to the driving motor 144.

When the starting button 160 is pressed the 40 contact points 150 and 152 are closed and current flows via the wire 145a and the wire 168 to the magnet 170 and via the return wire 175 to the negative side of the line. This energizes the magnet 170 and the contact arm 169 is attracted 45 causing the contact points 171 and 173 to close. The magnet 181 is not energized because the contact points 201 and 202 are always open when the machine is at rest or in its index position. As soon as the contacts 171, 173 are closed current 50 then flows via the wire 174 and the wire 145 to the motor 144 and returns via the wire 129 to the negative side of the line. This starts the mechanism to operating and almost immediately the contact points 186 and 188 are closed, the contact 55 points 192 and 195 are closed and the contact points 201 and 202 are closed due to the movement of the cams 189 and 198 respectively, thereby allowing the brush roll 120 to become energized.

60 The records engage the card lever contacts 220 and 223 respectively thereby opening the contact points 210, 212 and 215, 216.

When the start button 160 is released the motor 144 and the brush roll 120 continue to receive 65 current from the positive side of the line through the following circuits:

Current flows from the wire 145a via the wire 228, the contact arm 171, the contact points 178, 70 179 to the stationary arm 180 and thence via the wire 176 to the contact arm 154 from which it passes via the contact points 155 and 157 to the arm 156 and via the wires 167 and 168 to the magnet 170 causing the contact arm 169 to stick. 75 This keeps the contact points 171 and 173 en-

gaged so that current continues to flow via the wire 174 and 145 to the motor 144.

When the cam 189 allows the contact points 186, 188 to close a path in parallel with the circuit above described is set up. This path may be traced as follows:

From the wire 145a via the wire 240 to the contact lever 183 and thence via the contact points 186, 188 and the wires 190 and 145 to the motor 144. A branch circuit may be traced via 10 the wire 174, the contact points 173, 171, the contact arm 169, to the magnet 170 and via the return wire 175 to the negative side of the line.

At the end of each card cycle the lobe 189a moves the lever 183 thereby opening the contact points 186, 188 and interrupting the parallel circuit just described but the machine does not stop due to the circuit including the contact points 178, 179 and 155, 157. Therefore the machine 15 will continue to run and feed cards until a control record or a blank record fails to engage a card lever 220 or 223 respectively.

Due to the absence of a record at either card lever contact, for example, the card lever contact 220, the contact points 210, 212 fail to open with the result that when the cam 198 closes the contact points 201, 202 current will flow via the wire 207, the contact points 201, 202, the wire 208, the contact points 210, 212 to the contact arm 211 and thence via the wires 228, 182 to the 30 magnet 181.

The magnet 181 attracts the contact arm 171 and opens the contact points 178, 179 thereby interrupting the current flowing to the brush rolls 120.

The opening of the contacts 178, 179 also interrupts current flowing to the magnet 170 and allows the contacts 171, 173 to open thereby interrupting current flowing to the motor via the wires 174 and 145.

In case the stop button 162 is pressed during a card cycle current flowing via the wires 167, 168 to the holding magnet 170 and via the contacts 171, 173 is interrupted but current continues to flow to the brush roll 120 via the wire 229, the contact arm 171, the contact points 178, 179 and via the wire 239, the contact arm 191, the contact points 192, 195, the contact arm 194 and via the wire 122 to the shoe 121. Therefore the brush roll 120 will continue to receive current. The 40 motor will continue to run receiving its current via the wire 240, the contact points 186, 188 and the wires 190 and 145.

At the end of this card cycle the lobe 189a of the cam 189 cause the contact points 186, 188 to 55 open thereby interrupting current flowing to the motor 144 causing the machine to stop.

Upon the appearance of perforations on the control records one or more of the brushes 117 will become energized and impulses will flow via 60 the wire 118 to the jacks 119. The jacks 119 may be connected to jacks 114 by any suitable means, for example, by means of plug wires 127.

As previously described the jacks 114 form the terminals of the interposer control magnets 113 65 and impulses delivered to the jacks 114 flow through the magnet or magnets 113 and via a resistor 136 to the contact arm 133. A cam 135 has lobes which engage the bumper 134 to close contact points 131, 132 in time with the positioning of the successive index point positions at the sensing means and/or the punches.

Current flows from the arm 133 via the contacts 132, 131 to the stationary member 130 and thence to the return wire 129.

The contact points 131, 132 are bridged with a suitable resistor 138 in series with a suitable capacitor 131.

Due to the fact that the punch in any column 5 of the record to be produced may be connected to any brushes engaged by the control record, it is not necessary to provide the new and improved punch with the more or less complicated column cut-out contacts or skip bars of the prior 10 art, and due to the fact that the cards are fed through the machine in steps corresponding to the horizontal rows of index positions, the punching of a record is affected in twelve successive steps, whereas in the punches of the prior art the 15 vertical columns in the record are successively presented to the punches, making it necessary, where an entire record is to be reproduced, to feed the card through in eighty steps. From this it would appear that with the new and improved 20 device, work of this character can be done seven times as fast.

Due to the fact that the control magnets 113 operate on very low values of current, suitable bus jacks, jacks connected together in common, 25 may be provided in the plug board so that a plurality of control magnets may be connected to a single brush and these magnets could control punches in various portions of the card, thereby 30 reproducing a single column of the control record in a plurality of columns in the record to be produced, and it will be obvious to those skilled in the art that many other arrangements and combinations may be punched into a blank record 35 from a control record.

While a simple embodiment of the invention is shown and described herein, many changes in the arrangement of the parts and structure may be made without departing from the spirit of the invention as defined in the appended claims.

40 What is claimed is:

1. In a machine for perforating records having a plurality of rows of index values disposed along one dimension thereof and grouped in vertical columns along another dimension thereof, 45 a plurality of dies, a punch for each of said dies, a single mechanical member for driving said punches, an electrically controlled interposer for each punch adapted to associate its punch in driving relation to said member only while energized, record feeding mechanism including a series of feed rolls operating in steps to successively position said record with the index values along said first dimension beneath the punches, 50 each succeeding step presenting index values differing by one, whereby each stroke of the mechanical member causes the punches whose interposers have been actuated to perforate index positions in the record along said first dimension, and means for driving said member and 55 said feeding mechanism in definite timed relation to each other.

2. In a machine for perforating records having a plurality of rows of index values disposed along one dimension thereof and grouped in vertical columns along another dimension thereof, 60 a plurality of dies and punches therefor, a single mechanical member for driving said punches, an interposer for each of said punches, each adapted to be positioned between its punch and said member, electrical means for moving said interposers into and out of engagement with said member and said punches, means for actuating said member, and a series of feed rollers 65 and means for moving the same in steps to con-

trol the motion of said record after each actuation of said member.

3. A machine as claimed in claim 2 in which an associated device, having a sensing means operating in time relation to said machine, institutes impulses under control of a record passing through said sensing means for controlling said electrical means.

4. In a record controlled machine, a stack of control records, a stack of record media, a set of pickers for feeding said records, a set of pickers for feeding said media, feed rollers adapted to feed a record and a record media through said machine synchronously in steps, the movement of at least one of the steps being greater than the others, and a single shaft supporting and adapted to move all said pickers at the same time thereby advancing both a record and a record media to said feed rollers.

5. In a record controlled machine, a sensing means, punching means including a plurality of punches, a single mechanically driven member for driving all said punches, an interposer for each punch adapted to be positioned between the same and said member whereby the latter may drive the punches through the medium of said interposers, a control magnet for each interposer adapted to position its interposer between its punch and said member only during the time said magnet is energized, means to deliver a control record to said sensing means and a blank record to said punches simultaneously, said last means including a step by step feeding device comprised of a series of feed rolls maintaining positive control over the records adapted to advance them in steps corresponding to successive index position values, and interconnections between said sensing means and said control magnets.

6. In a record controlled machine in combination, control records having index points arranged thereon, blank records to be punched, a sensing device including a plurality of brushes, a plurality of punches and dies therefor, a single mechanical driving member adapted to drive all said punches, a plurality of interposers associated with said member in reciprocative relation, an electro-magnet for and mechanically linked to each of said interposers and adapted, when energized, to position and retain the latter between the punches and said member whereby the member may drive one or more punches through a blank record, means including a series of feed rollers for feeding a control record and a blank record through the machine in steps of index point intervals, and connections between said brushes and said magnets whereby said magnets are energized in accordance with data recorded in said control records.

7. A record controlled machine according to claim 4 in which both sets of said pickers are secured to and actuated by a single oscillatable shaft, and in which said feed rollers feed the record and the record media through the machine simultaneously in steps, and come to a definite stop between each successive step.

8. In a punching machine for perforating records having a plurality of rows of index points disposed along one dimension thereof, the points in each row being of like value, a plurality of dies disposed parallel to said rows, a plurality of punches for said dies, each of said punches being provided with a T shaped head, a mechanical member having a channeled slot formed therein engaging said punch heads and adapted to re-

- tract the punches from said dies, a plurality of interposers associated with said member in reciprocal relation, an electromagnet for and mechanically linked to each of said interposers and adapted only when energized to position and hold the latter between said heads and said member, means supplying impulses to said magnets, means for feeding blank records through the machine, and means driving said member to cause 5 certain of said punches to perforate said record.
9. In a perforating machine for record cards having thereon pluralities of index positions, a plurality of punches, a series of feed rollers adapted to feed a record in steps each coincident 10 with a plurality of index points of the same position significance, a cam for actuating said feed rollers, a mechanical member common to all said punches, and electrically controlled means adapted to determine which of said punches shall be 15 actuated by said member.
10. A machine as claimed in claim 6 in which machine control circuits are provided to cause the machine to continue to run and feed records as long as there are records of both kinds in the machine, said circuits including contacts to be 20 actuated by a starting button and contacts to be actuated by a stop button, the latter, when actuated by an operator, being adapted to stop the machine only after the card cycle then in progress is completed.
11. A machine as claimed in claim 6 in which machine control circuits are provided to cause the machine to continue to run and feed records as long as there are both kinds of records in the 25 machine, said circuits including instrumentalities adapted to de-energize the sensing means when the picker knives fail to advance a record card.
12. A device according to claim 2 in which the punches are provided with T shaped heads, and 30 in which the mechanical member is provided with a T slot engaging said heads, whereby said member may positively withdraw all actuated punches from said dies.
13. A device according to claim 2 in which the 35 mechanical member for driving the punches is provided at each end with a roller, and in which cams, mounted on a suitable power driven shaft, actuate said rollers.
14. A device according to claim 2 in which the 40 mechanical member for driving the punches is provided at each end with a roller mounted on a ball bearing, and in which cams, mounted on a suitable power driven shaft, actuate said rollers.
15. In perforating apparatus including a plurality of punches and dies therefor, means for 45 causing the actuation of one or more punches, said means including an interposer for each punch, and an electro-magnet for each inter- 50 poser for moving and holding the latter into operative relation to its punch only during the 55 time said magnet is energized.

16. A device according to claim 15 in which a sensing means including brushes is provided through which control records may be fed synchronously with the feeding of records to the punches and connections between said brushes and said electro-magnets whereby an impulse instituted by a control record will cause said electro-magnet to hold an interposer in operative relation to its punch only during the life of the impulse instituted by said control record. 10

17. In record controlled reproducing apparatus, a sensing means, a recording means including punches, a single mechanically driven member for driving said punches, an interposer for each punch adapted to be positioned between its 15 punch and said member whereby the latter may drive the punches, a control magnet for each interposer, means to deliver a control record to said sensing means and a record medium to said punches simultaneously, said last means including a step by step feeding device adapted to advance said records in steps, a cam member to actuate said feeding device in steps, and a second cam member to actuate said single mechanically driven member between the steps of said 20 feeding device, and interconnections between said sensing means and said control magnets whereby the latter will receive impulses isochronous with the sensing of data in said control record and causes its associated interposer to be 25 positioned between a punch and the mechanically driven member during said sensing interval.

18. In a record controlled machine, record feeding means for feeding and advancing records step by step through said machine including a 30 plurality of feed rolls, a cam having a lobe for each of said steps, a system of gearing associated with said feeding rollers and including a ratchet wheel controlled by said cam, a star wheel associated with said gearing, and a spring 40 loaded roller engaging said star wheel for accurately indexing said steps.

19. A device according to claim 18 in which at least one of the lobes on said cam is substantially larger than the others and adapted to feed the 45 record a distance greater than one index value.

20. In a record controlled machine, a stack of control records, a stack of record media, a set of pickers for feeding said records, a set of pickers for feeding said media, a shaft common to 50 and rigidly supporting both said sets of pickers, said shaft being spaced apart from the feeding edges of said stacks a distance less than that of the radii of said pickers, and means for oscillating said shaft to feed and advance both a record and a record media at the same time, said pickers being of such radius that while oscillating in unison with said shaft their outer ends describe arcs which are approximately tangent to the record and the record media respectively abutting the 55 ones being fed.

LINCOLN MATHEW KEEFE.
